MAGAZINE CONTROL MECHANISM

Albert A. Gordon and William M. Wattie, Worcester, Mass., assignors to Crompton & Knowles Loom Works, Worcester, Mass., a corporation of Massachusetts

Application August 1, 1933, Serial No. 683,145

2 Claims. (Cl. 139—232)

This invention relates to automatic looms in which a magazine is provided having two or more compartments for reserve bobbins.

It is the object of our present invention to provide control mechanism for such a magazine, by which mechanism the bobbins will be released from the different magazine compartments in a predetermined sequence.

More specifically, we have provided improved mechanism for releasing a bobbin from each compartment of a magazine in succession upon indication of weft exhaustion, and for repeating this sequence indefinitely.

Our invention further relates to arrangements and combinations of parts which will be herein-after described and more particularly pointed out in the appended claims.

A preferred form of the invention is shown in the drawings, in which

20 Fig. 1 is a side elevation, partly in section, of a portion of a loom embodying our improvements;

Fig. 2 is a plan view of certain parts, looking in the direction of the arrow 2 in Fig. 1, and

25 Figs. 3 and 4 are additional plan views, partly in section, and taken substantially along the lines 3—3 and 4—4 in Fig. 1.

Referring to Fig. 1, we have shown our invention embodied in a loom having a loom frame 10, drop boxes 11 vertically shiftable on a lay 12, and 30 having a weft carrier magazine 13 mounted in fixed position on the frame 10.

The magazine shown in the drawings is of the general type shown in the prior patent to Albert A. Gordon, No. 1,803,181, issued April 28, 1931, 35 and comprises two bobbin holders selectively movable downward in fixed guideways to present a bobbin B in position for rearward movement to transfer position by the transerrer 14.

The transerrer is mounted on a supporting 40 rod 15 connected by a link 16 to a head or plate 17 having a substantially L-shaped slot 18 therein. A cam 20 on the usual cam shaft 21 actuates a bell crank 22 having a stud 23 normally positioned in the segmental upper portion of the 45 slot 18 and oscillating freely therein.

An arm 25 is mounted on a cross shaft 26 which is controlled from weft detecting mechanism (not shown) at the opposite side of the loom, said arm being swung downward in the direction of the arrow a in Fig. 1 upon indication of weft exhaustion. A rocking lever 30 is pivoted at 31 and has a stud 32 at one end underlying the arm 25. The opposite end of the lever 30 is provided with a ledge or projection 33 underlying the head or 55 plate 17.

If the arm 25 receives a downward swinging movement when the stud 23 is at the forward end of the slot 18, the head 17 will be raised, bringing the stud 23 into the upright portion of the slot 18, whereupon the next swinging movement of the bell crank 22 will move the transerrer 14 rearward to transfer position and the transfer will thereafter take place on movement of the lay 12 to front center.

The parts thus far described in themselves form no part of our present invention and for a more complete description reference is made to the prior patent mentioned above.

Our present invention relates particularly to means for determining the order in which the 15 bobbin holders are depressed to present bobbins in the path of the transerrer 14.

The magazine 13 is provided with the usual rock shaft or color slide 40, which is movable axially to select the bobbin holder to be depressed, 20 and which is movable angularly to depress the selected bobbin holder.

For accomplishing the angular movement, the shaft 40 is provided with an offset arm 41 connected by a link 42 to the outer end of the arm 25 25 previously described. As the arm 25 is depressed to raise the head 17 to operative position, the shaft 40 is rocked to lower the selected bobbin holder.

Under certain conditions of loom operation it is 30 desirable to deliver bobbins alternately from each of the two bobbin holders and we have provided very simple mechanism for accomplishing this result.

For this purpose we provide a stud 50 on the 35 upper part of the slotted head or plate 17, and we provide a bell crank 51 mounted on a fixed stud 52 and having a slot 53 to receive the stud 50. The horizontal arm of the bell crank 51 is 40 connected by a link 55 to an arm 56 swinging about a fixed pivot 57. A cam disc 60 and ratchet plate 61 are freely rotatable on the stud 57 and are secured in fixed relation to each other.

A pawl 62 on the arm 56 engages the ratchet plate 61 and the pawl is advanced one tooth on 45 each rearward movement of the plate 17 and transerrer 14. As these parts return to normal or forward position, the pawl 62 turns the ratchet plate 61 angularly in an anticlockwise direction a distance corresponding to one tooth on the plate, 50 and similarly turns the cam disc 60.

As shown in the drawings, the cam disc 60 is provided with three raised portions 70 and with three depressed portions 71 alternating therewith. The cam disc 60 directly engages the rounded 55

end of the rock shaft or color slide 40, and the shaft is held in yielding engagement with the cam disc by a coil spring 72.

When the rock shaft 40 engages a depressed portion 71 of the cam disc 60, as shown in Fig. 1, the rock shaft 40 is positioned to depress the rearward or left hand bobbin holder in the magazine 13. When the cam plate 60 is advanced one space, so that the rock shaft 40 now engages a raised portion 70 of the cam disc, the rock shaft will be positioned to engage and depress the forward or right hand bobbin holder in the magazine 13.

While the cam disc shown in the drawings is adapted to cause delivery of bobbins from the front and rear bobbin holders alternately, it is obvious that by changing the outline of the cam disc any desired sequence may be provided.

We have thus provided very simple mechanism by which bobbins may be alternately delivered from two different bobbin holders, or may be delivered in any desired sequence. The moving parts are few in number and simple in construction and the mechanism is entirely reliable in operation.

Having thus described our invention and the advantages thereof, we do not wish to be limited to the details herein disclosed, otherwise than as set forth in the claims, but what we claim is:—

1. In a weft replenishing loom, a magazine having two bobbin compartments, transfer mechanism, and automatic means to present bobbins from said two compartments alternately to transfer position; said latter means comprising a shift-

able member on said magazine, a lever engaging a part of said transfer mechanism, an arm engaged by said lever, and a link connecting said arm to said shiftable member.

2. In a loom, weft replenishing mechanism including a magazine having a plurality of compartments each adapted to contain a plurality of bobbins, means to depress a selected bobbin compartment, a transfer member mounted to swing forward and rearward under said magazine and effective to transfer a bobbin from a depressed compartment rearwardly to an exhausted shuttle, actuating means for said transfer member including a continuously oscillated actuating member, a link connected to said transfer member and having a head with a substantially L-shaped slot therein, means to shift said head vertically to operative relation with said actuating member on indication of weft exhaustion, a rock shaft slidable axially on said magazine to determine the compartment to be depressed, a cam and spring cooperating to move said rock shaft alternately axially in opposite directions, pawl and ratchet means to move said cam intermittently, and actuating means for said pawl comprising a swinging arm on which the pawl is mounted, a lever, a link connecting said arm and lever and a device connecting said lever to said link head, whereby successive rearward and forward movements of said link and transfer member by said continuously oscillated actuating member effect return and feeding movements of said pawl.

ALBERT A. GORDON.
WILLIAM M. WATTIE.
